BAG LOCK.

Application filed May 1, 1924. Serial No. 710,214.

My invention relates to improvements in bag locks.

The objects of my invention are to provide a bag frame with an efficient and durable locking mechanism having wards formed integrally with a sheet metal longitudinally slotted cylinder and peculiarly adapted for variation, at small expense, in the position of the wards of successively formed locks, whereby different locks will require differently formed keys; to provide a locking mechanism which can be almost wholly constructed of sheet metal stampings; to provide locking mechanism for bag frames which cannot be unlocked by unauthorized persons; to provide locking mechanism which, when unlocked, may serve as an efficient catch of improved type for holding the jaws of a bag frame in closed position; and in general, to provide bags with more serviceable and less expensive locks than those heretofore used.

In the drawings:

Figure 1 is an elevation of my improved locking mechanism with the parts in unlocking position and showing fragments of an associated lock side band of a bag frame.

Figure 2 is a plan view of the locking mechanism, showing also a fragment of the hasp side band and hasps in slightly open position.

Figure 3 is a view similar to Figure 1, showing the parts in locking position.

Figure 4 is a sectional view drawn on line 4-4 of Figure 1.

Figure 5 is a detail view of the lock supporting frame and lock with key inserted.

Figures 6 and 7 are sectional views drawn respectively on lines 6-6 and 7-7 of Figure 5.

Figure 8 is a sectional view drawn on line 8-8 of Figure 7.

Figure 9 is a sectional view drawn on line 9-9 of Figure 8.

Figures 10 to 14 inclusive are detail isometric views of the parts of the lock and supporting frame.

Like parts are identified by the same reference characters throughout the several views.

The casing 1 contains a catch plate 2, which is of sheet metal, having upset hasp

engaging catches or shouldered extremities 3, which are adapted to enter apertures 4 in the hasps 5 to hold the jaws of the bag frame in closed position. The outer margins 6 of the catches 3 are beveled or inclined from the catch plate 2 toward their extremities in such a manner that the pressure of the hasps 5 against the beveled surfaces 6 will tend to retract the catch plate 2 away from the front wall of the casing. The catch plate is guided by posts 7, the ends of which are secured to the front and rear walls of the casing, and springs 8 coiled about these posts urge the catch plate 2 in the direction of the front wall of the casing. A detent plate 10 is held against the rear wall of the casing by the springs 8, said plate being also supported by the posts 7 which pass through apertures in this plate. The detent plate carries an arm 11, the extremity of which projects into a slot 12 in a locking slide 13 adapted to move longitudinally along the top wall 14 of the casing. The slide 13 is provided with a substantially V-shaped projection 15 extending from the rear side margins of the slot 12 intermediate of its ends. When the slide 13 is moved longitudinally of the casing in either direction, this projection 15 must engage and actuate the detent arm 11 to allow the slide to move to its other position of adjustment. The springs 8 allow the detent plate to tilt or move inwardly along the posts 7 to allow the extremity of the detent arm 11 to clear the projection 15. Thereupon, the detent plate 10 is restored to its normal position by the springs 8 and the detent arm engages in the slot 12 on the opposite side of the projection 15 to hold the slide 13 in the position to which it has thus been adjusted. The slide 13 is actuated by means of the key 18 having wards 19 adapted to pass between the inturned wards 20 on the relatively stationary longitudinally slotted cylinder 21, as best shown in Figures 8 and 9, the wards 20 and stop lips 26 being disposed upon the spaced margins of the longitudinal slot in the cylinder 21. A key guide 23 is mounted in the cylinder 21 and provided with a groove 24 in which the key 18 may slide when the guide 23 is rotated to bring its groove 24 into registry with the open side of the cylin-

der 21 between the wards 20 and stop lips 26. The key guide 23 is provided with integral collars 28 and 29 at its respective ends which substantially fill the cylinder 21, whereby this guide member may be inserted in the cylinder 21 before the wards 20 and stop lips 26 are pressed inwardly. When these parts are pressed inwardly, they enter the space between the collars 28 and 29 and 10 anchor the guide against longitudinal movement in the cylinder 21 while allowing it to rotate freely. The guide is provided with a reduced end portion 30 which, when the parts are assembled, has its inner end in 15 bearing contact with the catch plate 2.

The cylinder 21 is mounted in a frame which is generally U-shaped in form. This frame is also composed of sheet metal. Its outer end comprises a hollow headpiece 33 20 having inwardly projecting arms 34. These arms 34 are substantially parallel except as to the portions 35 which converge. The inner end portions 36 are also substantially parallel and are provided with reduced lip shaped extremities 37 adapted to pass through slots or apertures in the catch plate 2 to which these extremities are clinched by bending them upon the inner faces of the catch plate as shown at 38 in Figure 3, 30 whereby the arms 34 are anchored to the catch plate.

The cylinder 21 is held in position by a sheet metal holder 40 having curved cylinder embracing arms 41. The holder 40 is anchored to the catch plate by an arm 42 which bears against the inner face of the portion 36 of one of the arms 34 and is provided with a lip 43 which also extends through the catch plate 2 and is clinched thereto, as indicated at 44 in Figure 3. One of the curved arms 41 is indented or pressed inwardly at 45 and engages in a notch 46 in the cylinder 21 to prevent the latter from turning.

45 From the foregoing description of the key operated portion of the lock, it will be noted that it comprises a centrally grooved guide 23 rotatively mounted in the cylinder 21 which, in turn, is supported in and anchored 50 to, the concentric cylinder holder or mounting 40, the latter being anchored to the catch plate 2. All of these parts are, in turn, mounted for bodily movement within an auxiliary key receiving casing member 47 55 projecting outwardly from the wall of the casing 1, as clearly shown in Figures 1 and 3. The head 33 normally projects through the end of the casing member 47 and is adapted to be pressed inwardly to push the 60 catch plate 2 to hasp releasing position when the locking slide 13 has been moved to unlocking position. All of the parts except the guide 23 are formed of sheet metal, pressed or stamped into shape as above described.

65 The casing member 47 is preferably provided

with cylindrically rounded portions and the head 33 has similarly rounded portions 48 adapted to conform to the rounded portions of the member 47 in which they slide.

It will of course be understood that when 70 the slide 13 is in locking position, as shown in Figure 3, the bag cannot be opened until a key has been inserted in the guide 23, which key has wards 19 adapted to pass between the wards 20 on the relatively stationary 75 cylinder 21. The key must also have a wing 50 adapted to engage in a recess or notch 51 in the locking slide 13, whereby said slide may be shifted from locking to unlocking position. The key preferably has a projection 53 on its inner end, which enters a circular aperture or recess in the catch plate 2 when the key is in a position to rotate within the cylinder 21.

By varying the positions of the wards 20 80 on the cylinders 21 and correspondingly varying the positions of the wards 19 on the keys, the structure in all other respects remaining the same, it is obvious that locks may be successively made, each of which requires 85 a different operating key or, if desired, the locks may be made in sets, wherein each individual member of the set may be operated by lock keys but in which no key can be utilized to lock or unlock a member of 90 a different set.

I claim:

1. A bag lock, comprising the combination with a main casing having an auxiliary key receiving casing projecting from one 100 wall, a resiliently mounted catch plate in the main casing and a key operated slide adapted, in one position, to hold the catch plate in locking position, of a longitudinally slotted cylinder within the auxiliary casing 105 and provided with inturned wards, an enclosing holder therefor having a projecting arm anchored to the catch plate, a supporting frame also having arms anchored to the catch plate and having an end piece provided with a slot adapted to allow a key to enter the cylinder, and a rotary key guide within said cylinder adapted to guide an inserted key to a position for actuating said 110 slide.

2. In a bag lock, the combination with a resiliently mounted catch plate and a casing therefor having a lock receiving projection, of a key actuated slide mounted to slide within the casing projection, a key receiving longitudinally slotted cylinder therein provided with inturned wards, a key guide within the cylinder, and a holder for the cylinder provided with a longitudinally projecting arm, said slide and holder being anchored to the catch plate, and said cylinder, holder, slide and casing being formed of stamped sheet metal.

3. In a bag frame locking mechanism, the 120 combination with a spring supported catch

plate, a yoke-shaped finger piece frame secured thereto and having a head provided with a key hole slot, of a ward carrying member within the frame, and a sheet metal holder therefor anchored to the catch plate and provided with portions embracing said ward carrying member to hold it in position.

4. In a bag frame locking mechanism, the combination with a spring supported catch plate, a yoke-shaped finger piece frame secured thereto and having a head provided with a key hole slot, of a ward carrying member within the frame, and a sheet metal holder therefor anchored to the catch plate and provided with portions embracing said ward carrying member to hold it in position, said catch plate being slotted and said holder and frame each having an arm extending through the slot and clinched upon the inner face of the catch plate.

5. In a bag lock, the combination with a casing, a resiliently mounted hasp engaging catch member therein adapted to be yieldingly pressed to releasing position, a slide controlling yielding movement of the catch member, a frame connected with the catch member and having a head piece projecting through the casing and provided with a key hole, a longitudinally slotted cylinder supported from the catch member and within the head piece and provided with inturned key controlling wards, and a key adapted to enter said cylinder through said key hole and to engage and actuate said slide, said key being formed for rotation within said cylinder when in slide actuating position.

6. In a bag lock, the combination with a casing, a resiliently mounted hasp engaging catch member therein adapted to be yieldingly pressed to releasing position, a slide controlling yielding movement of the catch member, a frame connected with the catch member and having a head piece projecting through the casing and provided with a key hole, a longitudinally slotted cylinder supported from the catch member and within the head piece and provided with inturned key controlling wards, and a key adapted to enter said cylinder through said key hole and to engage and actuate said slide, said key being formed for rotation within said cylinder when in slide actuating position, and said frame head piece being guided by the casing in its catch actuating movements.

7. In a lock having a catch member and a slide for locking said catch member, the combination with a barrel having wards, of a key for operating said slide and having wards adapted to cooperate with the wards on said barrel, and a slotted rotatable key guide journaled in said barrel adapted to receive said key in said slot, said barrel comprising a piece of sheet metal bent to form a cylinder having longitudinally extending

and peripherally spaced margins provided with integral projections bent inwardly of the cylinder to form wards.

8. In a lock having a catch member and a slide for locking said catch member, the combination with a non-rotatable ward carrying barrel, of a key for operating said slide and having wards, and a slotted rotatable key guide journaled in said barrel and adapted to receive said key in said slot, said barrel comprising a longitudinally split cylinder having spaced longitudinal margins, one of which is provided with integral wards projecting inwardly of the cylinder and adapted to receive between them the wards on said key.

9. In a lock having a catch member and a slide for locking said catch member, the combination with a key for operating said slide and having wards, of a rotatable key guide having a pair of spaced annular shoulders and a longitudinal slot for receiving said key, and a non-rotatable barrel inclosing said shoulders and providing a barrel therefor, said barrel having wards extending into the space between said shoulders and adapted to co-operate with the wards on said key.

10. In a lock having a catch member and a slide for locking said catch member, the combination with a key for operating said slide and having wards, of a rotatable key guide having a pair of spaced annular shoulders, and a longitudinal slot for receiving said key, and a non-rotatable barrel inclosing said shoulders and providing a bearing therefor, said barrel comprising a longitudinally split cylinder having spaced longitudinal margins, one of said margins being provided with integral inturned wards adapted to extend into the space between the shoulders on said guide and to co-operate with the wards on said key.

11. In a lock having a catch member and a slide for locking said catch member, the combination with a key for operating said slide and having wards, of a rotatable key guide having a pair of spaced annular shoulders and a longitudinal slot for receiving said key, and a non-rotatable barrel enclosing said shoulders and providing a bearing therefor, said barrel comprising a longitudinally split cylinder having spaced longitudinal margins, one of said margins being provided with integral inturned wards and the other of said margins being provided with integral inturned stop lips, said wards and stop lips being spaced apart to permit the wards on said key to pass between them and being extended into the space between the shoulders on said guide, said wards and lips co-operating with the wards on said key to permit the key to be rotated in said barrel.

12. In a lock having a catch member and

- a slide for locking said catch member, the combination with a barrel, of a key for operating said slide and having wards, and means for rotatably journaling said key in 5 said barrel, said barrel having wards and stop lips, each ward and lip being circumferentially spaced from each other to permit the wards on said key to pass between them, said wards and lips co-operating with the 10 wards on said key to permit the key to be rotated in either direction in said cylinder.
13. In a lock having a key provided with wards, a barrel having wards adapted to co-operate with the wards on said key, said 15 barrel comprising a piece of sheet metal bent to form a cylinder having longitudi-

nally extending and peripherally spaced margins provided with integral projections bent inwardly of the cylinder to form wards.

14. In a lock having a key provided with 20 wards, a barrel having wards and stop lips circumferentially spaced therefrom, said wards and lips being adapted to co-operate with the wards on said key, the barrel comprising a piece of sheet metal bent to form 25 a cylinder having longitudinally spaced margins, one of said margins having integral projections bent inwardly to form wards and the other of said margins having integral projections bent inwardly to form stop lips.

FRED GRIMM.
